INVENTOR:

J. H. Racey Jr.

United States Patent Office.

JOSEPH H. RACEY, JR., OF NEW YORK, N. Y.

Letters Patent No. 80,766, dated August 4, 1868.

IMPROVED REFRIGERATING-CHAMBER.

The Schedule referred to in these Letters Patent and making part of the same.

TO ALL WHOM IT MAY CONCERN:

Be it known that I, JOSEPH H. RACEY, Jr., of the city, county, and State of New York, have invented a new and useful Improvement in Refrigerating-Chambers; and I do hereby declare that the following is a full, clear, and exact description of the same, reference being had to the accompanying drawings, forming a part of this specification, in which—

Figure 1 represents a plan of a refrigerating-chamber, constructed according to my improvement, as seen from above, with the upper part of the case removed.

Figure 2, a vertical section of the same, in the plane indicated by the line $x x$ in fig. 1, and

Figure 3, a transverse sectional elevation through the centre of the chamber, at right angles with fig. 2.

Similar letters of reference indicate corresponding parts in the several figures.

This invention relates to a novel arrangement of those parts of the interior of a refrigerator or refrigerating-chamber which contain the ice or refrigerating-substance or substances, whereby a very large surface is obtained by a very simple construction, and provision is afforded for obtaining an effective ventilation of the refrigerator or chamber through which the foul or warm air ascends, and by which a circulation is kept up, a ventilating-pipe being provided at the top of the structure for that purpose.

In order that others may be better enabled to understand the construction and operation of my improvement, I will proceed to describe it with reference to the drawings.

A is the box or case of the refrigerator; B, door to said case, for insertion or removal of such articles as it is designed to preserve; E E are side boxes or receptacles, situated on each side, within the interior of the chamber, and secured to the upper part of the case A by a flange and screws, or other suitable arrangement, intended to contain the refrigerating-substance, which may be plain ice, or ice and salt, or other refrigerating-mixture, and which is inserted through doors, F F, cut in the top of the case A. From these receptacles there project downwards, to near the bottom of said case, waved or corrugated plates G G, united at the ends of the structure, and of a tapering or converging character, so as to be apart internally at their upper ends, where they join the receptacles E E, but gradually approaching each other, and meeting at their angular formation below, at which point the pockets H H, thus formed, establish an open junction with horizontal receptacles or troughs I I. These pockets, throughout their entire depth, or nearly so, serve, with the receptacles E E, to hold the refrigerating-material, while the troughs I I contain the water produced by the melting of the latter, and which is allowed to run off through waste-pipes J J, which pass through the walls of the box or case A, and are slightly elevated for the purpose of regulating the level to which the water is allowed to collect. Thus the receptacle E, pockets H, and trough I, being connected together in a water-tight manner, form one chamber, the tapering form of which prevents the ice, which is broken or ground to a given size, from settling too low therein, and the trough I, being filled with water from the melting ice, closes the discharge-aperture, and prevents any circulation of air through the chamber containing the refrigerant, whilst the pipe K allows the escape of cool air or gases generated therein, into the body of the structure, which causes a circulation, and expels the warmer air through the inverted cone and ventilating-pipe a. Any number of these ice-chambers may be used, in proportion to the size of the chamber in which they are placed, and converging, corrugated, or fluted form, presents a more extended cooling-surface within the same space, and which increases in an upward direction, where the air is naturally warmer.

What I claim as my invention, and desire to secure by Letters Patent, is—

1. The pockets H, constructed of a series of flutes or corrugations, connected in a tight manner at their upper ends with the chamber E, and at their lower ends with the trough I, said trough being provided with a waste-pipe, J, and vent-pipe K, so arranged that the water from the melting ice shall accumulate in the trough, and prevent the circulation of air through the refrigerant contained in said pockets, substantially as set forth.

2. The combination of the vent-pipe K with the inverted cone-vent a, arranged and operating essentially as shown and described.
